H. V. CROON

VAPORIZER AND CARBURETOR

Filed Jan. 21, 1922

UNITED STATES PATENT OFFICE.

HERMAN V. CROON, OF CHICAGO, ILLINOIS.

VAPORIZER AND CARBURETOR.

Application filed January 21, 1922. Serial No. 530,761.

To all whom it may concern:

Be it known that I, HERMAN V. CROON, a citizen of the United States, residing at Chicago, in the county of Cook and State of Illinois, have invented a certain new and useful Improvement in Vaporizers and Carburetors, of which the following is a full, clear, concise, and exact description, reference being had to the accompanying drawings, forming a part of this specification.

My invention pertains to vaporizing carburetors.

The theory upon which the present carburetor and vaporizer operates is an entire departure from the theory of operation of practically all commercial carburetors of the present day. Heretofore, the feed of liquid fuel has generally been in liquid spray form from a fuel feeding nozzle or orifice discharging under the combined influence of the engine suction and the aspirating action of the high velocity stream of air flowing past the fuel nozzle. In the present instance the fuel is subjected to a suction of sufficient intensity to produce a gaseous fuel vapor from the liquid fuel, this fuel vapor being fed to the air stream as the principal or sole fuel component of the mixture. This latter method produces a completely gasified mixture as distinguished from the wet, imperfectly formed mixture which so frequently results from the projection of the fuel in liquid form into the air stream. Consequently, by the present theory there is avoided a large part of the well known carburetion difficulties arising from these improperly formed mixtures, such as "loading" or accumulations of condensation on the manifold walls; lack of responsiveness to acceleration; crank case dilution resulting from incompletely vaporized fuel failing to burn and descending into the crank case past the piston; and other difficulties well known to those skilled in the art.

According to the preferred manner of practicing the present theory, the vaporization of the fuel by suction may be accomplished by subjecting a substantially quiescent body of fuel to the suction; or by agitating or projecting the fuel and subjecting this projected or moving body of fuel to suction; or by a combination of both. Heat may also be employed in connection with the suction for increasing the rate of vaporization of the fuel.

In the embodiments hereinafter shown, it

will be noted that the proper production of vapor according to this theory is not dependent in any sense upon the maintenance of a strictly accurate fuel level. Where the vaporization is from a substantially quiescent body of fuel it is only necessary to maintain a body of fuel with a sufficiently extensive area or free vaporizing surface to insure the generation of the requisite volume of vapor. Any fluctuation or tilting of the level of this vaporizing fuel surface does not influence the operation of the carburetor, as the generation of vapor is not materially affected by such fluctuations or inclinations of the fuel level. This is of advantage in all fields of carburetion, where inclination or change of fuel level will frequently modify the proportions of the mixture undesirably, but is of greatest significance in aviation practice where the motion and the various maneuvers of the aircraft make the maintenance of any definite fuel level extremely difficult.

The control of this type of vaporizing carburetor is comparatively simple and certain in action, owing to the definite relation which will generally exist between the intensity of suction and the rate of vaporization of the fuel, this rate of fuel vaporization being primarily responsive to the intensity of suction.

Another desirable characteristic accruing to the present method of carburetion is the ability to automatically raise or draw the fuel from the supply tank to the carburetor without the intervention of vacuum feed tanks, a pressure feed from the supply tank, or a gravity head. By subjecting the fuel in the vaporizer to a suction of a vaporizing degree sufficient suction is available at the carburetor during all engine speeds to afford a direct suction lift of the fuel to the carburetor.

In the accompanying drawings illustrating a preferred embodiment of my invention:

Figure 1 is a vertical sectional view through the present carburetor;

Fig. 2 is a fragmentary side elevational view of the same; and

Fig. 3 is a vertical sectional view of a modified construction.

The vaporizer and carburetor is embodied in a casting 5 comprising a fuel vaporizing chamber 6 and an air passageway 7. The passageway 7 is illustrated as being vertical, but it will be obvious that the carburetor

may be of the horizontal tube type as well. The air passageway 7 opens into a carbureting chamber 8 of greater diameter, the air passageway 7 being preferably formed by dividing the tubular chamber 8 by a vertical wall or partition 9, extending down to the bottom of the vaporizing chamber 6. The discharge of combustible mixture from the carbureting chamber 8 is controlled by a conventional throttle valve 11 mounted on a transverse shaft 12. The discharge of air into the carbureting chamber 8 is controlled by a throttle or swinging flap valve 13 which is also mounted on a control shaft 14 extending through the side walls of the casting. The two valves 11 and 13 are connected together for joint operation in such a manner as to maintain a vaporizing suction in the carbureting chamber 8, as I shall presently describe.

On the other side of the wall or partition 9 a vapor passageway 15 extends down into proximity to the top of the vaporizing chamber 6. This vapor passageway is separated from the interior of the vaporizing chamber 6 by an inclined wall 16 having a vapor feeding port 17. The discharge of vapor through this port is controlled by a needle valve 18 which projects diagonally out of the carburetor through a diagonal enlargement or boss 19. The valve 18 may have direct screw threaded engagement in the boss 19, but is preferably threaded in a bushing 21 which is in turn threaded into the boss 19. A cap 22 threads down over the bushing 21 and seals the needle adjustment against leakage of suction. In lieu of the arrangement shown, it will be obvious to those skilled in the art that this needle valve may be arranged for manual control from the dash or steering column through the intervention of a suitable control rod extending thereto, or this needle valve may be arranged to operate simultaneously with the throttle valve through any well known system of linkage for controlling the size of the vapor port 17 in accordance with the position of the throttle valve.

The fuel is supplied to the vaporizing chamber 6 through an inlet plug 24 which screws into the removable cover 25 closing the top of the chamber 6. The supply pipe is adapted to have threaded connection in an obvious manner with the upper end of the plug 24, the lower end of the bore of this plug constituting an inlet port 26 adapted to be controlled by a needle valve 27 and float 28. The stem of the needle valve 27 is guided in the hub of the guide bracket 29 secured to the under side of the cover 25. The inlet port 26 and the end of the needle valve 27 may be formed on a relatively obtuse taper. In the operation of the carburetor a relatively high suction prevails above the fuel level in the vaporizing chamber 6 and this causes any fuel entering through the port 26 to be projected into the chamber at a relatively high velocity owing to the considerable difference of pressure between the chamber 6 and the supply tank. This fuel is projected by the obtuse taper on the end of the needle valve 27 into a conical curtain of liquid fuel broken up into a finely subdivided state. This is an alternative feature which may or may not be employed to augment the volume of fuel vapor obtained from the free vaporizing surface in the chamber 6.

The requisite suction for obtaining the aforesaid vaporizing action is obtained by linking the valves 11 and 13 so that the throttle valve 11 will have a certain lead of opening over the air valve 13. The purpose of this is to maintain in the carbureting chamber 8 and passageway 15 a vacuum or suction of sufficient degree to vaporize the fuel in the chamber 6 throughout substantially the entire range of engine speeds. As shown in Fig. 2, the outer end of the throttle shaft 12 carries an operating arm 32 which has pivotal connection with an operating rod 33 extending to the control mechanism, such as the accelerator pedal and steering column control lever. The pivot 34 has connection through a link 35 with an operating arm 36 on the projecting end of the air valve shaft 14. An eye 37 engages over the pivot 34 and is screw threaded for reception in the threaded socket in the end of the link 35, whereby the link may be conveniently extended or shortened. The end of the operating arm 36 is extended down diagonally to receive a slot 38 through which extends a bolt 39 passing through the end of the link 35. The engagement of the bolt 39 in the slot 38 affords a lost motion connection between the link 35 and operating arm 36, whereby the throttle valve 11 is opened to a limited extent prior to opening movement of the air valve 13. The end of the operating arm 36 is provided with a hook or lug 41 over which engages one end of a tension spring 42, the other end of this spring being secured to the body of the carburetor at 43.

The admission of air to the air passageway 7 is controlled by a choke valve 44 which swings on a transverse valve shaft 45. The outer end of this shaft has an operating arm 46 connecting through a rod 47 with any suitable dash or steering column control. The needle valve 27 has no pivotal or fixed connection with the float 28 but merely rides on a plate 50 on the top of the float. This permits the float to incline or shift under change of level without binding the needle valve. The float is confined against shifting entirely out from under the needle valve by a guide post 48 which projects upwardly from a removable nut or plug 49 screwing into the bottom of the vaporizing

chainber. The removal of the plug 49 affords a convenient drain outlet in the bottom of the vaporizing chamber 6 for draining the liquid contents thereof.

5 In the operation of the device, the cooperative relation between the valves 11 and 13 always maintains a relatively high suction in the carbureting chamber 8 and the vapor passageway 15. When the throttle 11 is initially opened, the air valve 13 lags behind the opening movement of the throttle to such an extent that the volume of air admitted from the passageway 7 is insufficient to satisfy the suction in the carbureting 10 chamber 8, with the result that a relatively high suction prevails in this chamber and the vapor passageway 15 at this time. Similarly, when the throttle 11 has been moved to its full open position, the flow of air from 15 the passageway 7 is still insufficient to completely satisfy the suction in the carbureting chamber 8, with the result that a relatively high suction is also maintained in the carbureting chamber at this time. This high 20 suction is transmitted through the vapor port 17 into the vaporizing chamber 6. Here it lowers the boiling point of the liquid fuel and results in the relatively broad surface of fuel giving up a considerable volume of 25 fuel vapor. This vapor is drawn out through the port 17 under the control of the needle valve 18 and, passing upwardly through the passageway 15, mingles with the air stream entering the carburetion chamber 30 8 from the air passageway 7. The fuel which is thus supplied to the air stream is an ideal vapor completely vaporized and devoid of liquid particles which form such a large part of the discharge from the conventional aspirating fuel jet, and which cause 35 the loading, deposition of carbon and crank case dilution hereinbefore mentioned. If desired, the emission of vapor may be augmented by arranging the entering fuel to 40 discharge in a finely subdivided state whereby the suction in the chamber 6 will have intimate contact with the fuel for vaporizing the same. It will be obvious that the high suction in the upper part of the chamber 45 6 will insure a reliable suction feed of the fuel from the supply tank to the carburetor at all engine speeds.

50 In Figure 3 I have illustrated a modified construction wherein the fuel vapor is discharged from a jet or nozzle over which sweeps the air stream in its flow through the carbureting chamber. The carbureting chamber 8' has a vapor nozzle 51 projecting into the lower end of the chamber, this nozzle extending upwardly from an intermediate plate 52 which closes the bottom of the carbureting chamber 8' and the top of the fuel vaporizing chamber 6'. The complete carburetor assembly in this form shown in 55 Figure 3 consists of the upper casting 53,

the plate 52 and the bowl 6' forming the fuel vaporizing chamber. The carbureting chamber 8' is defined in a sleeve 54 constituting part of the casting 53, and this sleeve terminates short of the plate 52 so as to 70 provide an annular air admission port 55 to the bottom of the carbureting chamber 8'. This annular port is below the tip of the vapor nozzle 51 so that the high velocity stream of air entering through this port will 75 sweep upwardly and laterally across the tip of the nozzle 51, a venturi baffle 60 aiding in directing the flow of air, thereby adding the velocity suction of the air stream to the static suction of the carbureting chamber in 80 producing a high aggregate suction available at the tip of the nozzle. An adequate static suction is maintained in the carbureting chamber 8' by a sleeve valve 56 which reciprocates either inside or outside of the 85 sleeve 54 and controls the size of the air admission port 55. A link 57 has pivotal connection with this sleeve valve 56 and also with lugs 58 which extend from the throttle 11'. As a result of this arrangement, 90 operation of the throttle also operates the air admission valve 56 to control the suction in the carbureting chamber, analogously to the operation of the valves 11 and 13 of the preceding embodiment. A choker 95 control of the air supply may be obtained by providing a jacket 59 to surround the air admission port 55, and arranging a choker valve 61 in the intake 62 to this jacket. 100

As previously remarked, the high suction transmitted into the vaporizing chamber 6' through the nozzle 51 results in the fuel feeding into the chamber 6' under a considerable head. To insure complete closure of the fuel intake valve when the level reaches a relatively high point, I have arranged a multiplied leverage between the float 63 and the inlet valve 64. An arm 65 extends from the float and has pivotal connection at 66 in the vaporizing chamber, this arm having a short extension 67 which operates to control the seating or unseating of the valve 64. This valve and its cooperating valve seat may be tapered to secure the fuel 110 dispersing action previously described, if desired. A needle valve 68 extends upwardly from the bottom of the vaporizing chamber, through a hole in the float 63, and controls the size of the port in the nozzle 51. 115

120 As remarked in the general statement of the invention, I also contemplate employing heat for increasing the rate of vaporization of the fuel. This may be provided for by subjecting all or a restricted part of the vaporizing chamber 6 or 6' to exhaust heat or heat from the cooling water circulating through the cylinder jackets. To this end the vaporizing chamber 6 or 6' may be provided with a jacket 71 for heating a 125 130

large or small area of the vaporizing bowl, and having an inlet 72 and an outlet 73 adapted for connection with the exhaust manifold or with the cooling circuit, in a manner obvious to those skilled in the art. However, in the actual operation of a device such as shown in Figure 1 I have found that the suction alone is capable of vaporizing a relatively large quantity of fuel.

10. I claim:

1. In a vaporizer and carburetor for internal combustion engines, a carbureting chamber having an air inlet and a mixture outlet adapted to be connected to the intake of an internal combustion engine whereby said carbureting chamber is under suction when the engine is operating, a vaporizing chamber having liquid fuel inlet means and vapor outlet means, said vaporizing chamber being otherwise closed and said vapor outlet means being in open communication with said carbureting chamber to effect suction in said vaporizing chamber by the suction created in said carbureting chamber, said vaporizing chamber having non-absorbent walls defining a body of liquid except for its level, a float in said vaporizing chamber, and a valve operated by said float and controlling said inlet means, whereby the liquid fuel in said vaporizing chamber is prevented from rising at any point above the level determined by said float and valve.
2. In a vaporizer and carburetor for internal combustion engines, a carbureting chamber having an air inlet and a mixture outlet adapted to be connected to the intake of an internal combustion engine whereby said carbureting chamber is under suction when the engine is operating, a vaporizing chamber having liquid fuel inlet means and vapor outlet means, said vaporizing chamber being otherwise closed and said vapor out-

let means being in open communication with said carbureting chamber to effect suction in said vaporizing chamber by the suction created in said carbureting chamber, said vaporizing chamber having non-absorbent walls defining a body of liquid except for its level, a float in said vaporizing chamber, a valve operated by said float and controlling said inlet means, whereby the liquid fuel in said vaporizing chamber is prevented from rising at any point above the level determined by said float and valve, a throttle in said mixture outlet, and a valve in said air inlet operatively connected with said throttle.

3. In a vaporizer and carburetor for internal combustion engines, a carbureting chamber having an air inlet and a mixture outlet adapted to be connected to the intake of an internal combustion engine, whereby said carbureting chamber is under suction when the engine is operating, a vaporizing chamber having liquid fuel inlet means and vapor outlet means, said vaporizing chamber being otherwise closed and said vapor outlet means being in open communication with said carbureting chamber to effect suction in said vaporizing chamber by the suction created in said carbureting chamber, said vaporizing chamber having non-absorbent walls defining a body of liquid except for its level, a float in said vaporizing chamber, a valve operated by said float and controlling said inlet means, whereby the liquid fuel in said vaporizing chamber is prevented from rising at any point above the level determined by said float and valve, and means for applying heat to said vaporizing chamber.

In witness whereof, I hereunto subscribe my name this 14th day of January, 1922.

HERMAN V. CROON.
